SHEET FEEDING DEVICE

Frederick W. Storck, Arlington, Mass., assignor to
Standard Mailing Machines Company, Everett,
Mass., a corporation of Massachusetts

Application November 7, 1940, Serial No. 364,671

8 Claims. (Cl. 271—59)

This invention relates to sheet feeding and more particularly to a sheet guiding device which may be readily actuated in a determinate step-by-step manner for guiding sheets in desired registering positions transversely of the sheet support.

While not limited thereto, the present invention presents many advantages for use in association with duplicating machines such as are used by commercial and manufacturing establishments, their related departments and various types of offices. It is well known that in such businesses various systems have been devised that require the producing and recording on forms only such information as is advisable or necessary on the particular form, and to vary the information on additional and/or like forms such as the particular system may require.

An example of such a system may be found in numerous order systems such as are employed in factories, and wherein an original order sheet is made out containing a multiplicity of items comprising a complete order. Selected items are taken from the main order and reproduced or posted on an individual order in connection with a proper heading corresponding to the complete original and embodying the subject matter, and then these separate orders are distributed to the various departments throughout the factory. An example of devices for arranging the subject matter for such a system is disclosed in U. S. Letters Patent No. 2,218,304, issued to Frederick W. Storck on October 15, 1940.

To duplicate the selected information of the original order in proper position on the form, the clear form sheet must be guided and fed to the duplicating elements in a manner whereby both the desired item or items or form will register when engaged with one another.

Accordingly, one of the primary objects of the present invention is to provide a sheet guide that may be readily and positively positioned so that a sheet edge placed against the guide may be fed to the master duplicating or printing elements in a manner whereby the form on the sheet will register with the selected matter on the original.

Another object of the invention is to provide a sheet guide that may be moved in a determinate step-by-step manner so that sheets positioned against the guide in a sequential manner will register with consecutive spaced items on the original.

A further object of the invention is to provide a sheet guide that may be moved by increments

and positively positioned in a predeterminately spaced manner.

A still further object of the present invention is to devise a mechanism that is simple and efficient in character and which may be readily actuated to a number of different indicated positions for the purpose of functioning as a guide in the positioning of a sheet so that, when the sheet is advanced, it will register for engagement with other elements.

The foregoing objects are merely stated as illustrative of the invention and are not to be construed as a limitation thereof, as other objects and advantages will be apparent from the following detailed description of the invention and more particularly set forth in the claims appended hereto and forming a part hereof.

While not limited thereto, in the present instance the invention is shown in association with a so-called "wet process" duplicating machine that is particularly adaptable to the previously referred to system.

Fig. 1 is a vertical section of a duplicating machine with a supporting cabinet and having the invention embodied therewith.

Fig. 2 is a section taken substantially along line 2—2, Fig. 1.

Fig. 3 is a plan view of a portion of the duplicating machine with a sheet support and guide.

Fig. 4 is a transverse section taken substantially along line 4—4, Fig. 3.

Fig. 5 is a section taken substantially along line 5—5, Fig. 4.

Fig. 6 is a section taken along line 6—6, Fig. 4.

Fig. 7 is a section taken substantially along line 7—7, Fig. 4.

Fig. 8 is an end view, partially in section, of the yieldable stop device for the sheet guide actuating mechanism.

Fig. 9 is a section taken along line 9—9, Fig. 8.

The duplicating machine

In the present illustrated form the duplicating machine is provided with opposed side frames 45 10, only one of which is shown in the drawings. A rotatable drum 11 is supported between the side frames 10 and may be rotated in a desired manner by means (not shown). A suitable pressure roller 11a engages with the periphery of the drum. Associated with the drum 11 and rotated in relation thereto is a gear 12 that meshes with and rotates an intermediate gear 13. The machine is provided with a pair of rollers 14, 15 that are also rotatably supported in the side frames 50 10 and in this instance the upper roller 14 is

provided with a gear 16 that meshes with the intermediate gear 13 and by means of which the roller 14 is positively rotated. The roller 15 is rotated by means of its frictional contact with the driven roller 14.

Disposed in front of the rollers 14, 15 is a moistening unit 17 that engages with the roller 14 and applies moisture to the face of this roller as the roller is rotated.

A machine of the above general character is fully shown and described in U. S. Reissue Letters Patent No. 19,951, issued to Frederick W. Storck on April 28, 1936; therefore, further detailed description is thought to be unnecessary in the present instance.

Master printing elements

The primary master 18, Fig. 3, is secured to the rotatable printing drum in any suitable manner. This master 18 is formed with numerical items 18a that are preferably arranged in a spaced relation substantially equal to the distance of the double spacing of lines as is effected by the usual typewriting machine. A secondary master 19 is superimposed relative to the primary master 18 and attached to the drum 11 so as to be movable longitudinally of the drum 11 and to a position adjacent the selected numerical item 18a. This secondary master 19 carries information that is to be duplicated, in combination with the selected data 18a on the primary master, upon a clear form or sheet 20.

Sheet support and guide

Suitably supported by the side frames 10 is a sheet support 21 that is used ordinarily to support a stack of clear sheets that are to be fed singly to the printing elements which may be of the usual character embodied in machines adapted to make a number of duplicate copies of master subject matter. Usually, the sheet support is provided with means against which the edge of the stack may be positioned for proper alignment to be advanced into registering engagement with other elements. Such a means may embody up-turned flanges 21a, 21b of the sheet support 21, together with an adjustable member 22 that is slidably supported on the sheet support.

In the present instance, the adjustable member 22 is substantially L-shaped in cross section with its base 22a resting on the upper surface of the sheet support. This base 22a is provided with a guide portion 23 that engages in a transverse slot 21c, formed in the sheet support 21, and functions to maintain the flange 22b in a parallel relation to the sheet support flange 21a.

Sheet guide actuating mechanism

The guide portion 23 is provided with a depending pin 24 that engages with a rotatable threaded member 25 disposed below the sheet receiving surface of the sheet support 21, and this member 25 is supported in suitable bearings 25d, 25e affixed to the sheet support 21. For the present purpose, the thread 25a, of the member 25, is formed with a required lead so that a one-half revolution of the member 25 will move the pin 24 a distance equal to two usual typewritten line spaces. Of course, the thread 25a may be designed so as to give a desired lead and adapted to specific requirements.

Associated with the threaded member 25 is a clutch, generally indicated at 26, that includes a housing 27 secured to the reduced diameter por-

tion 25b of the member 25. A head member 28 is disposed in the housing 27 and is adapted to rotate freely on its portion 25b of the threaded member 25. This head is provided with notches 28a in its peripheral face in which balls or rollers 29 are disposed and these members 28 are urged into a driving position between the head notches 28a and housing 27 by means of compression springs 30. The head 28 is provided with a hub 28b to which a pulley 31 is secured. The assembly of the head 28 and pulley 31 is retained in relation to the housing 27 by means of a washer 32 fixed to the end of the shaft 25b by means of a screw 33.

15 This clutch arrangement is such that when the pulley 31 and head member 28 are rotated in a clockwise direction, Fig. 6, the clutching members 29 serve to rotate the housing and member 25 in the same direction. When the pulley 31 and head member 28 rotate in a contra-clockwise direction, the clutching members are ineffective and, therefore, the housing 27 and member 25 remain stationary.

20 A chain 34 or other form of linkage is disposed partially about the face of the pulley 31 and in a positive manner engages with a pin 35 secured in the pulley so that movement of the chain 34 in either direction will cause rotation of the pulley 31. One end of the chain 34 is secured to an upwardly extending portion 36a of a foot treadle 36 pivotally supported by suitable brackets 37 disposed in the machine supporting cabinet 38. The other end of the chain 34 is attached to one end of a pull spring 39 that is suitably attached to a stationary part 40 within the cabinet 38. A stop 41 is provided so as to limit movement of the treadle in one direction while the treadle is urged in the direction of the stop 41 by means of a compression spring 42.

Positioning stop

25 Adjustably secured to the end portion 25c of the threaded member 25 is a disc 43 having a pair of studs 44, 45 secured in the outer end face thereof. The studs support a pair of rollers 46, 47 which, in this instance, are in the form of anti-friction bearings. These rollers 46, 47 engage with an enlarged head 48a of a plunger 48 slidably mounted in a suitable bracket 49 secured to the sheet support 21. A spring 50 encircles the plunger 48 in a suitable manner that functions to urge the plunger head 48a into yielding engagement with the rollers 46, 47 and thus this assembly functions as a yieldable stop for arresting the rotative movement of the threaded member 25 in a determinate position.

30 It is to be noted that, in the present structure, two rollers 46, 47 are employed so that the threaded member 25 is provided with two determinate stop positions for each complete revolution. Obviously, the design of the threaded member may be varied as to the lead of the thread and the number of determinate stop positions arranged for particular requirements.

Operation

35 In a preferred arrangement, the machine is provided with a foot treadle 52 and linkage 53 to the power connecting means of the machine so that the operator may depress the treadle 52 to cause a complete effective duplicating cycle of the machine.

40 It will be assumed that the primary master 18 is already secured to the drum 11 and the secondary master 19 correctly positioned relative to

item 6 of the primary master 18 and that items 1 to 5, which are now covered by the secondary master 19, have already been duplicated. The guide 22 is positioned on the indicating mark with the numeral 6 as this mark corresponds to item 6 that is to be duplicated. The clear form sheet 20 is then positioned against the guide 22 and advanced to the feeding rollers 14, 15. When the operator depresses the machine operating treadle 52, the machine begins its operative cycle and the form sheet 20 is advanced and engaged between the printing drum 11 and roller 11a to be engaged in registration with the master copies as the drum 11 is rotated.

After the machine has completed its cycle of operation, the secondary master 19 is then positioned adjacent the next succeeding item, in this instance item 7. The operator then depresses the sheet guide positioning treadle 36, in the direction indicated by the arrow, Fig. 2, thus rotating the pulley 31 in a clockwise direction, the clutch locking elements 29 causing the housing 27 and threaded member 25 to be rotated therewith. As aforesaid, the elements are arranged, in the present instance, to rotate the member 25 for a one-half revolution. Rotation of the thread 25a, formed on the member 25, causes the pin 24 to move the sheet guide 22 to the left and positions the guide on the next succeeding mark (7) to correspond to the item (7) that is to be next duplicated. The operator then repeats the sequence of operation by first placing the clear form sheet against the guide 22 and advancing the positioned sheet 22 to the feed rollers 14, 15.

Having thus described my invention, what I claim is:

1. A device of the character specified having a sheet support, a sheet guide on said support with means adapted to actuate said guide, said means embodying a rotatable member associated with said guide, together with means for intermittently rotating said member in a manner whereby said guide is moved in a step-by-step sequence.

2. A device of the character specified having a sheet support, a sheet guide on said support with means adapted to actuate said guide, said means embodying a rotatable member associated with said guide with means for rotating said member, yielding means associated with said rotatable member is urged to a determinate stop position, member whereby rotative movement of said

3. A duplicating machine having effective op-

erating cycles in combination with a sheet positioning support, a sheet guide on said support with means adapted to actuate said guide, said means embodying a rotatable member associated with said guide with means for intermittently rotating said member relative to the operative cycles of said machine.

4. A device of the character specified having a sheet support, a sheet guide on said support with means adapted to actuate said guide, said means embodying a rotatable member associated with said guide, manually operable means for rotating said member in a manner whereby said guide is moved in a step-by-step sequence.

5. A device of the character specified having a sheet support, a sheet guide on said support with means adapted to actuate said guide, said means embodying a rotatable member associated with said guide, a spring pressed stop for determinately positioning said member with means for rotating said member between determinate positions and whereby said guide is moved in a step-by-step sequence.

6. A device of the character specified having a sheet support, a sheet guide on said support with means adapted to actuate said guide, said means embodying a rotatable member associated with said guide, a determinate yieldable stop for said member with means for rotating said member between determinate stop positions.

7. A device of the character specified having a sheet support with an opening therein, a sheet guide on said support and having a portion thereof extending into said opening, a rotatable threaded member disposed below the sheet receiving surface of said support and in engagement with said portion of the guide, together with means for rotating said member in a manner whereby said guide is actuated in a step-by-step sequence.

8. A device of the character specified having a sheet support with an opening therein, a sheet guide on said support and having a portion thereof extending into said opening, a rotatable threaded member disposed below the sheet receiving surface of said support and in engagement with said portion of the guide, a determinate yieldable stop for said rotatable member with means for rotating said member between determinate stop positions.

FREDERICK W. STORCK.
